Hugh K. Wagner,
ATTORNEY.

UNITED STATES PATENT OFFICE.

WYLIE E. MURRAY, OF ST. LOUIS, MISSOURI.

CIGARETTE-HOLDER.

1,269,491.

Specification of Letters Patent. Patented June 11, 1918.

Application filed July 23, 1917. Serial No. 182,145.

To all whom it may concern:

Be it known that I, WYLIE E. MURRAY, a citizen of the United States, residing at the city of St Louis, in the State of Missouri, have invented certain new and useful Improvements in Cigarette-Holders, of which the following is a specification.

The object of this invention is to provide a holder for cigarettes and cigars that will require no attention by the user, but leave him free to follow any occupation and, at the same time, to have his "smoke" handy. Ordinary holders for such articles accumulate saliva and nicotin, which is objectionable, but impossible in this one. In the holders now in use, it is necessary to use a pin or other implement to remove the short butt-end, but that is obviated in the present device.

The chief advantage of this invention over those now on sale is that it makes it unnecessary to lay the cigar or cigarette down between puffs or to hold it in the fingers, interfering with any other occupation. It affords a convenient way to hold a cigarette in connection with the hand, so that, when a puff is desired, the hand is merely moved toward the mouth of the user without its being necessary to pick up the cigarette or cigar in the fingers, and when removed from the mouth it is unnecessary to lay it down on a piece of furniture, endangering the furniture. It is common knowledge that much furniture and the like is marred by burns from cigars and cigarettes laid temporarily thereon with the burning part supposed to be at a safe distance from the edge, but which left too long or carelessly placed produce damage.

Card-players, office and factory workers, and drivers of automobiles will find this invention of particular utility for the reason just stated and because of its allowing them to smoke without interfering with their other employment.

Another advantage of this holder is that

it prevents stains and odors on the fingers. In the case of dentists, barbers, and others the absence of odors from the fingers is very desirable.

In the accompanying drawings, forming part of this specification, in which like numbers of reference denote like parts wherever they occur, the device is illustrated on an enlarged scale, and

Figure 1 is a perspective view;

Fig. 2 is a sectional view on the line 2—2 in Fig. one; and

Fig. 3 depicts a modification.

This device consists of a pair of non-concentric rings 1 and 2, swiveled together at 3. One of these rings, designated as 1, is like a finger-ring and intended preferably to be worn upon the index finger of the hand. The ring 2 is roughened upon its interior 4 in any suitable manner, so as to prevent the cigarette 5 (or cigar) held therein from slipping out.

The rings will be made of suitable sizes, the ring 2 being made larger for cigars and smaller for cigarettes. Usually the ring 1 will be larger than the ring 2. The ring 1 may be made of sizes varying like the sizes of finger-rings or it may be split at 6 or any other suitable point as shown in the modification illustrated in Fig. 3, so as to be expansible to fit fingers of various sizes. The ring 1 or the ring 2, or both, may be made of expansible material, so as to be adapted to fit any size of finger or smoking material.

Any material may be used in the manufacture of this device, either very cheap, so that it can be given away as an advertising device, or more expensive, so as to make it suitable for sale by jewelry stores.

It will be noted that the respective ends of the swivel 3 are countersunk in the interior of the rings 1 and 2.

Having thus described this invention, I hereby reserve the benefit of all changes in form, arrangement, order, or use of parts,

2
as it is evident that many minor changes may be made therein without departing from the spirit of this invention.

I claim:

5 A device of the character described comprising a pair of non-concentric rings, the one being adapted to be worn upon a finger and the other being superimposed thereon and connected thereto and being adapted

to serve as a holder for a cigarette or the 10 like, the connections between said rings being such that said cigarette-holding ring may be bodily rotated to shift the same in a plane with or at right angles to the finger ring.

In testimony whereof I hereunto affix my signature.

WYLIE E. MURRAY.
